PACKER

Luther F. Lamb, Dallas, Tex.

Application August 31, 1936, Serial No. 98,802

6 Claims. (Cl. 166—10)

This invention relates to new and useful improvements in packers.

One object of the invention is to provide an improved packer which is particularly adapted 5 for use in packing off well casing.

An important object of the invention is to provide an improved well packer which includes an elastic packing element which is arranged to be anchored within a well casing, said element being normally in a retracted or unpacked position, and a separate member adapted to be lowered into the packing element to distort the same into packing position, whereby the member may be readily removed from the casing and the packing element restored to its normal retracted position, without removing the packing element from the casing.

Another object of the invention is to provide an improved well packer which is constructed in two units, one of which carries the elastic packing element; this latter unit having means at some distance below the packing element for anchoring the unit in the well casing; whereby when the packing element is in packing position 20 the engagement of the element with the casing wall and the anchoring means provide two points, substantially some distance apart, of contact with the casing, whereby the unit is rigidly held in proper position and "wobble" or sway of the unit 25 is eliminated, which greatly reduces the wear on the packing element.

A further object of the invention is to provide an improved well packer having a tubular mandrel for the passage of well fluid, with means 30 within the mandrel arranged to be engaged by a lifting tool, said means being constructed so as not to interfere with flow of fluid through the mandrel.

Another object of the invention is to provide 40 an improved well packer which is constructed in two units one of which carries the packing element and the other of which has means for engaging the element to expand the same, with means for axially alining the upper unit with 45 the lower unit, whereby the packing element is distorted equally.

A still further object of the invention is to provide a lifting tool for raising and lowering 50 a well packer which is provided with adjustable guide means for guiding the tool axially through the well casing, the adjustability of said guide means permitting the tool to be employed in various sizes of casing.

55 A construction designed to carry out the in-

vention will be hereinafter described, together with other features of the invention.

The invention will be more readily understood from a reading of the following specification and by reference to the accompanying drawings, in 5 which an example of the invention is shown, and wherein:

Figure 1 is an elevation of the upper portion 10 of a well packer, constructed in accordance with the invention,

Figure 2 is a similar view of the lower portion thereof,

Figure 3 is a transverse, vertical, sectional view of the packer set within the well casing,

Figure 3a is a partial, transverse sectional view 15 of a modified form of the device,

Figure 4 is an elevation of the lifting tool,

Figures 5 and 6 are partial elevations of the 20 lower end of the tool, taken at right angles to Figure 4,

Figure 7 is a transverse, vertical, sectional view 25 of the lower unit and showing the lifting tool in elevation and engaged therewith,

Figure 8 is a transverse, vertical, sectional view 30 of a modified form of the invention,

Figure 9 is an elevation of a modified form 35 of lifting tool,

Figure 10 is an elevation of still another form 40 of lifting tool, and

Figure 11 is a horizontal, cross-sectional view, 45 taken on the line 11—11 of Figure 10.

This application is filed as a continuation in 50 part of my co-pending application filed June 8, 1935, Serial No. 25,587.

In the drawings, the numeral 10 designates the 55 usual well casing which extends downwardly throughout the length of the well hole. The packer, which is constructed of a lower unit A and an upper unit B is lowered into the well and positioned at any desired point therein. The 40 lower unit A, as is clearly shown in Figures 2 and 3, includes an annular packing collar or element 11 which is constructed of rubber, rubber compound or any other elastic material which is capable of distortion and which will form a seal. The annular packing element is provided with an axial bore 12 which has its lower end slightly enlarged as shown at 13. This enlarged portion of the bore snugly engages over the upper end 45 of a supporting sleeve 14, which sleeve is formed with an external annular flange or shoulder 15, whereby when the packing element is engaged over the upper end of said sleeve, the lower edge 50 of said element is supported on the annular 55

shoulder. It is preferable to mold the packing element to the sleeve.

The lower end of the sleeve 14 is slightly reduced and is internally threaded to receive the upper end of a section of tubing 16. The lower end of the tubing section is connected by a suitable coupling collar 17 with an anchor tube 18. As is clearly shown in Figure 3, the anchor tube 18 may be of any desired length and has its lower end provided with perforations 19 in the usual manner. The length of the tube 18 will, of course, control the position of the packing element 11 within the well casing 10, so by varying the length of said tube which rests on the bottom of the hole the location of said packing element is controlled. When the unit A is lowered into the well casing and the anchor tube 18 strikes the bottom of the hole, it will be seen that the packing element is positioned. Well fluid may enter the opening 19 in the tube 18 and flow upwardly through the tubing section 17, sleeve 14 and packing element. It is noted that the weight of the unit A will cause the lower end of the tube 18 to embed itself in the formation so as to rigidly support the lower end of the unit.

The extreme upper end of the packing element 11 is flared outwardly as shown at 12' so that the bore 12 of the packing element will readily receive an inverted conical head 20 which is preferably constructed of metal, although it may be made of any suitable material. It will be seen that when the head 20 enters the bore the packing element 11 will be distorted outwardly in a radial direction so that its outer surface will contact the wall of the well casing 10. The head 20 is provided with an integral internally threaded collar 21 at its upper end, and this collar receives the lower threaded end of a section of tubing 22. The upper end of the section 22 is connected by a coupling 23 with an elongate sleeve 24 which is provided with a fishing neck 25 at its upper end. The sleeve 24 is formed with a plurality of perforations or openings 26 throughout its entire length. For guiding the unit B which carries the annular inverted conical head 20 at its lower end axially within the casing 10, the sleeve is provided with radially extended guide wings 27 which are preferably located near the upper end thereof.

After the unit A has been lowered into the well casing to its proper position with the anchor tube 18 resting on bottom and the lowering tool withdrawn, the unit B may then be lowered into said casing by the pump rods or a suitable tool (not shown) which is engaged with the fishing neck 25 at the upper end of the unit B. The guide wings 27 on the sleeve 24 will guide the unit downwardly within the casing and will assure the head 20 entering the bore 12 of the packing element 11. It is noted that the flared upper end 12' of the bore 12 will aid in guiding the head 20 within the packing element. The weight of the unit B will force the head 20 downwardly within the bore 12 of the packing element, thereby distorting said element so that its outer surface engages the wall of the well casing 10, whereby the well casing is packed off. The guide wings 27 not only guide the unit B during its downward movement in the well casing but also serve to position the head 20 axially of the packing element whereby an equal distortion in all radial directions of said element is had.

With the head 20 inserted within the packing

element 11, as is clearly shown in Figure 3, the outer surface of said element is forced into a tight frictional engagement with the wall of the casing so as to form a seal. This frictional engagement not only serves to seal off the well casing but also provides a gripping means whereby the upper end of the unit A is firmly and rigidly held within the well casing. This frictional engagement of the element provides means for steadyng and rigidly holding the upper end of the unit A in place, while the anchor tube 18 engaging the bottom of the hole forms a gripping means to steady the lower end of the unit A. Thus, it will be seen that fastening of the unit A within the casing is accomplished at two points which are a comparatively great distance apart. When the units A and B are positioned within the well casing, as shown in Figure 3, it will be obvious that the well fluid will enter the perforations 19 in the lower end of the anchor tube 18 and will pass upwardly through the tubing section 16, sleeve 14 and then through the bore of the packing element 11. The fluid will then flow upwardly through the annular head 20, tubing section 22, and into the perforated sleeve 24. From the sleeve, the fluid will escape through the perforations 26 therein and into the well casing from where it will flow to the top of said casing. It is noted that the fishing neck 25 at the upper end of the perforated sleeve 24 is provided with a bore 25' and although some fluid may escape through this bore, the majority of said fluid will flow outwardly through the perforations 26.

When it is desired to remove the upper unit B for any reason whatever, the fishing neck 25 at the upper end of said unit may be engaged by a suitable tool (not shown) and the entire unit B raised to the surface of the well casing. Since the head 20 is carried by the upper unit B, it will be raised therewith and as soon as the head is removed from the bore 12 of the packing element 11, said packing element will immediately return to its normal position out of packing engagement with the casing wall. Thus, it will be seen that the unit B may at any time be removed without disturbing the packing element 11. Therefore, since the packing remains in the well, the wear on the packing caused by its frictional engagement with the interior wall and couplings of the casing 10 during the removal or insertion thereof, as is the usual practice, is eliminated. The packing element 11 remains in the casing at all times and need not be removed until its permanent removal therefrom and, therefore, the life of said packing element is greatly increased.

After the upper unit B has been removed from the well casing, and it is desired to remove the lower unit A, any suitable tool for removing said lower unit may be employed. However, I prefer to employ a tool as shown in Figures 4 to 6. This tool comprises an elongate tubular section 30 which is provided with a pair of J-slots 31 in its lower end. It is noted that the J-slots are located diametrically opposite each other in the lower end of said section and the lower end of the vertical leg 31' of each J-slot is open. Near the upper end of the section a pair of diametrical slots 32 are formed. These slots are positioned one above the other and are located at right angles to each other. Guide members 33 are inserted in the slots and are secured therein by bolts 34 which receive nuts 35 on their extended end. The guide members have their outer faces

curved and are substantially equal in length to the inner diameter of the casing 10, whereby as the tool is lowered within the casing, the members 33 serve to guide the same axially within said casing. The upper end of the section 30 is provided with the usual fishing neck 36 and also with a coupling 37, whereby the sucker rod (not shown) may be attached thereto.

The lower end of the tubular section 30 is inserted within the unit A through the bore of the packing element 11, sleeve 14 and tubing section 16, as is clearly shown in Figure 7. For connecting the lifting tool with the unit A, the section of tubing 16 is provided with a transverse pin 38 which is rigidly mounted in the wall of said section and which extends diametrically across the interior thereof. In connecting the tool to the unit A, the section 30 is entered into the tubing section 16 and the opened lower end 20 of the J-slot 31 will engage the transverse pin 38. The lower edge of the section 30 adjacent each J-slot may be inclined upwardly at a slight angle, as shown at 30 in Figures 5 and 6, so that said pin will be directed or guided into the J-slots. 25 By lowering the section 30 and then rotating said section it will be seen that the pin 38 will enter the horizontal leg of each J-slot and then by exerting an upward pull on the tool, it will be obvious that the unit A may be raised within the 30 well casing. In a similar way, the engagement of the tool with the pin 38 will permit lowering of said unit into said casing. It is noted that the provision of the transverse pin within the tubing section does not in any way restrict the flow of 35 fluid through said section because it takes up so little space that there is substantially no decrease in the cross-sectional area of the tubing section at this point. It is also pointed out that the location of the transverse pin 38 is not to be limited to being disposed within the tubing section 16, for it is obvious that said pin could be located within the sleeve 14, as is clearly shown in Figure 3a. By raising the transverse pin 38 within the unit A, it is possible to make the tubular section 30 of the lifting tool of a smaller 40 length.

It is noted that if desired, a pumping barrel or combination, not shown, may be mounted between the perforated sleeve 24 and the head 20. The pump rod would extend down through the bore 25, in which a bronze bushing (not shown) is usually inserted, in the fishing neck 25 at the upper end of the unit B and then downwardly through the perforated sleeve 24 and into the barrel. In this manner, the packer could be used 55 in combination with a fluid pump when it is necessary to pump the well.

In Figure 8, I have shown a slightly modified form of the invention. In this form, instead of employing the anchor tube 18 for supporting the lower end of the unit A, I provide a slip assembly, whereby the lower end of said unit may be securely locked to the casing wall. As is clearly shown in Figure 8, the slip assembly comprises a mandrel 40 having a slip cone 41 made integral therewith. A plurality of slips 42 are slideable vertically on the cone 41 and are carried by resilient bars 43 which have their lower ends secured to a cage 44 slideable on the mandrel. Normally, 60 the cage is moved with said mandrel since it is provided with a hook 45 engaged with a gudgeon 46 on the mandrel. Suitable friction springs 47 have their upper ends secured to the cage 44 while their lower ends are fastened to a collar 48 65 slideable on the mandrel. This slip assembly 70

common in the oil field art and no claim is made thereto. Also the invention is not to be limited to the particular type of slip assembly shown but any suitable type for anchoring the lower end of the unit A may be employed. When the slips are set, it will be obvious that the lower end of the unit A is rigidly secured to the casing. Then when the unit B is lowered so that the head 20 engages the packing element 11 to distort the same, it will be obvious that there are two points 10 of contact, substantially some distance apart, which rigidly fasten the unit A within the casing 10.

In Figures 9 and 10, I have shown modified forms of the lifting tool, by which the lower unit 15 A is raised and lowered within the well casing. In the form shown in Figure 4, it is noted that the guide wings 33 which are held in place by the bolts 34 must be replaced when it is desired to use the tool with various size casings. In other 20 words, when a six-inch casing is used, guide wings having a length of six inches must be bolted in the section 30. Similarly, when a larger or smaller casing is used other guide wings 33 must be substituted. To overcome this objection, a 25 fishing tool 50, as shown in Figure 9 is provided. The tool comprises a tubular mandrel 51 having a fishing neck 52 at its upper end. The lower end of the mandrel is provided with J-slots 53 similar to the slots 31 in the form shown in 30 Figure 4. A collar 54 is slidably mounted on the mandrel 51 and is held in adjusted positions thereon by a set screw 55. Toggle links 56 which are pivoted to each other at 57 have their upper and lower ends pivoted to the collar 54 and to 35 the lower portion of the mandrel 51. By raising and lowering the collar 54 with relation to the lower pivot of the toggle links, it is obvious that said links may be extended or retracted from the mandrel. In this way, it is possible to adjust 40 the links so that they will ride on the wall of any size casing. This eliminates the necessity of substituting guide wings as is necessary in the form shown in Figure 4.

In Figures 10 and 11, still another form of the 45 lifting tool is shown. In this form, a pair of guide wings 60 extend through slots 61 formed in the tubular section 30' which forms the main body of the tool. As is clearly shown in Figure 50 10, the guide wings 60 are inclined and are disposed at right angles to each other. A single bolt 62 passes through the body 30' and through both guide wings 60 and receives a nut 63 on its outer end. Each guide wing 60 is provided with a plurality of openings 60' along its length and it 55 will be seen that by passing the bolt 62 through the various openings 60', it is possible to extend or retract the outer end of the guide wings 60. In this manner, it is possible to adjust the wings so as to adapt the tool to various size casings.

What I claim and desire to secure by Letters Patent, is:

1. A well packer including, a pair of co-acting units, one unit comprising a tubular support, an annular elastic packing element carried by the upper end of the support and normally disengaged from the well casing, means on the support and spaced from the packing element for fastening said unit in the well casing, means within the tubular support adapted to be engaged by a 65 lifting tool whereby the unit may be raised or lowered in a well casing, the second unit including a tubular support, and means carried by the lower end of the second unit for engaging within the annular packing element to expand the same 70

- radially into packing engagement with the well casing, there being an axial passage extending through both units, whereby fluid may flow upwardly therethrough.
5. 2. A well packer including, a pair of co-acting units, one unit comprising a tubular support, an annular elastic packing element carried by the upper end of the support and normally disengaged from the well casing, means on the support and spaced from the packing element for fastening said unit in the well casing, the second unit including a tubular support, guide wings in said support for engaging the casing wall to guide the support axially in the casing, and means carried by the lower end of the second unit for engaging within the annular packing element to expand the same radially into packing engagement with the well casing, there being an axial passage extending through both units, whereby fluid may flow upwardly therethrough.
10. 3. A well packer including, a pair of co-acting units, one unit comprising a tubular support having its lower end open, an annular packing element mounted on the upper end of said support, whereby fluid may flow upwardly through the support and element, lifting means for raising and lowering the support including a tubular body having J-slots at its lower end, a transverse pin within the tubular support adapted to be engaged in the J-slots, the second unit including, a tubular support, and means having a fluid passage therethrough carried by the lower end of the support for engaging within the packing element to expand the same radially into engagement with the well casing.
15. 4. A well packer including, a pair of co-acting units, one unit comprising a tubular support hav-
- ing its lower end open, an annular packing element mounted on the upper end of said support, whereby fluid may flow upwardly through the support and element, lifting means for raising and lowering the support including a tubular body 5 having J-slots at its lower end, adjustable means on the body for guiding the same axially within the well casing, a transverse pin within the tubular support adapted to be engaged in the J-slots, the second unit including a tubular support, and means having a fluid passage therethrough carried by the lower end of the support for engaging within the packing element to expand the same radially into engagement with the well casing.
5. The combination with a well packer having, 15 a tubular mandrel with a transverse pin therein of a lifting tool for raising and lowering the packer in a well casing including, a tubular body having diametrically opposite J-slots in its lower end for engaging said pin to connect the tool and 20 packer, and guide wings extending outwardly from the body for guiding the tool axially within a well casing.
6. The combination with a well packer having a tubular mandrel with a transverse pin therein 25 of a lifting tool for raising and lowering the packer in a well casing including, a tubular body having diametrically opposite J-slots in its lower end for engaging said pin to connect the tool and 30 packer, guide wings extending outwardly from the body for guiding the tool axially within a well casing, and means for varying the length of the portion of the wings extending from said body, whereby the tool may be used in various size casing.

LUTHER F. LAMB.
